UNITED STATES PATENT OFFICE.

JOHN C. BARBER, OF CHICAGO, ILLINOIS.

CENTER-BEARING.

SPECIFICATION forming part of Letters Patent No. 779,572, dated January 10, 1905.

Application filed December 21, 1903. Serial No. 186,138.

To all whom it may concern:

Be it known that I, JOHN C. BARBER, a citizen of the United States, residing at Chicago, in the county of Cook and State of Illinois, have 5 invented certain new and useful Improvements in Center-Bearings; and I do hereby declare the following to be a full, clear, and exact description of the invention, such as will enable others skilled in the art to which it appertains 10 to make and use the same.

My present invention relates to center-bearings for cars, and especially to those employing antifriction devices.

The invention has for its object to simplify 15 and improve the construction of said center-bearings; and to such ends it consists of the novel devices and combinations of devices hereinafter described, and defined in the claims.

The invention is illustrated in the accompanying drawings, wherein like characters indicate like parts throughout the several views.

Figure 1 is a plan view, with some parts broken away, showing a center-bearing designed in accordance with my present invention. Fig. 2 is a transverse vertical section taken on the irregular line $x^2 x^2$ of Fig. 1, and Fig. 3 is a side elevation of the center-bearing.

The numeral 1 indicates the upper member, and the numeral 2 the lower member, of the 30 center-bearing, the former having a depressed central hub 3 and the latter having a depressed central portion or hub-seat 4. The hub 3 and the hub-seat 4 are formed with coincident perforations or seats 5 for the king-bolt or 35 pintle. (Not shown.) Outward of the hub 3 and depressed seat 4 the members 1 and 2 are formed with beveled and outwardly-flaring annular roller-bearing surfaces 6, between which are interposed a plurality of radially-40 disposed outwardly-flaring conical roller-bearings 7. In their larger and outer ends the rollers 7 are provided with axial pin-seats 8. Since this construction employs smooth 45 roller-bearing surfaces—that is, bearing-surfaces without depressions therein—means must be provided for holding the said rollers properly spaced in the proper radial arrangement. This I accomplish by an extremely simple and efficient device, which consists

simply of a loose thrust-ring 9, having on its 50 inner surface a plurality of inwardly-projecting radial trunnions 10, which fit one into the seat 8 of each roller 7. Preferably the thrust-ring 9 is also formed with bosses 11 at the bases of the trunnions 10 for direct engagement with the outer ends of the rollers 7 to directly receive the outward thrust from the rollers. As is evident, the thrust-ring 9 is supported simply by the rollers and has 55 frictional contact with no other parts. The 60 rollers may be very quickly applied to and removed from the trunnions of the said thrust-ring by simple endwise movements and without requiring the removal of any bolt, pin, or other device. 65

The bearing members 1 and 2, respectively, are preferably formed with downturned and upturned marginal flanges 12 and 13, which form a housing inclosing the thrust-ring 9.

To limit the extreme pivotal movements of 70 the members 1 and 2 in respect to each other, one of the members—to wit, as shown, the upper member—is provided with a pair of heavy flanged stop-lugs 14, that work between laterally-spaced pairs of stop-lugs 15 on the 75 lower member 2.

The center-bearing above described while of small cost is very strong and is efficient for the purposes had in view.

It will of course be understood that the device described is capable of modification within the scope of my invention as herein set forth and claimed. 80

What I claim, and desire to secure by Letters Patent of the United States, is as follows: 85

1. In a center-bearing, the combination with the upper member 1, having the depressed hub 3, and the lower member 2, having the depressed hub-seat 4, the said two members having the annular outwardly-flaring roller-bearing surfaces 6, of the conical rollers 7, radially disposed and interposed between said bearing-surfaces 6, said rollers having, in their outer ends, the axial seats 8, and the thrust-ring 9 having the inwardly-projecting trunnions 10 engaging, one in the seat 8 of each roller 7, substantially as described. 90

2. In a center - bearing, the combination with upper and lower members 1 and 2, one of said members having stop-lugs 14, and the other thereof having the coöperating pairs of 5 laterally-spaced stop-lugs 15, of rollers interposed between bearing-surfaces of the said members 1 and 2, substantially as described.

In testimony whereof I affix my signature in presence of two witnesses.

JOHN C. BARBER.
